UNITED STATES PATENT OFFICE.

DOMENICO MARRAZZO, OF BROOKLYN, NEW YORK, ASSIGNOR OF ONE-THIRD TO JOSEPH L. TRIVISONNO AND ONE-THIRD TO SAVERIO BALZANO, BOTH OF BROOKLYN, NEW YORK.

ROTARY HAND FAN.

Application filed June 15, 1921. Serial No. 477,631.

To all whom it may concern:

Be it known that I, DOMENICO MARRAZZO, a subject of the King of Italy, residing at Brooklyn, in the county of Kings and State of New York, have invented new and useful Improvements in Rotary Hand Fans, of which the following is a specification.

This invention relates to improvements in rotary hand fans and has for its primary 10 object to provide a device which is light and compact in construction and which may be readily placed in the pocket of the user for transportation.

Another object of the invention is to provide a fan having foldable blades arranged in such a manner that when not in use the device may be stored in a minimum amount of space.

As a further object the invention contemplates the provision of blades having stops arranged thereon for automatically limiting the movement of said blades in such a manner that as soon as power is applied to the device the blades will be thrown to open position, and as soon as the operation ceases the blades will automatically fold.

Still another object of the invention is to provide a gear train having a clutch arranged thereon in such a manner as to cause 20 the blades to rotate in one direction.

With these and other objects in view the invention consists in the novel construction, combination and arrangement of parts which will be fully set forth in the following specification, claimed and illustrated in the accompanying drawing, in which,

Figure 1 is a side view of this improved fan, showing the blades in folded position,

Figure 2 is a face view of Figure 1, showing the blades in open position,

Figure 3 is an edge view of the interior mechanism,

Figure 4 is a face view of Figure 3,

Figure 5 is a bottom plan view of Figure 3,

Figure 6 is a fragmentary face view of the fixed blade,

Figure 7 is a view similar to Figure 6 of one of the foldable blades, and

Figure 8 is a view similar to Figure 7 of the other foldable blade.

Referring to the drawings in detail, the numeral 10 designates a hollow housing having a slot 11 in its upper side for the ac-

commodation of the reciprocating plunger of 65 the actuating mechanism. As illustrated in the drawings, the housing is hollow and circular in formation and is of sufficient size to contain the mechanism illustrated in Figures 3 to 5.

The actuating mechanism above referred to comprises a base plate 12, provided on one face with a longitudinal guide 13 over which the U-shaped plunger 14 is adapted 65 to slide. Extending laterally from the base plate 12 is an arm 15 which is pierced to receive the end of a shaft 16, the opposite end of which is rotatably received in an arm 17 formed on the cover plate 18 which is attached by suitable securing means such as screws 19 to the guide 13, and serves to retain the plunger 14 in proper position.

Formed along one of the marginal edges of the plunger 14 is a plurality of rack teeth 20 which mesh with a pinion 21 which is loosely mounted on the shaft 16 and is arranged by means of a suitable clutch mechanism to drive a gear 22 in one direction. Said clutch comprises the ratchet teeth 45, 70 preferably cut on the inside of the gear 22 and a suitable ratchet pawl 46, mounted on the shaft 16 and secured to the pinion 21. This gear 22 meshes with a pinion 23 which is secured to the drive shaft 24 upon which the fan blades are mounted. A retractile 75 coil spring 25 is arranged in such a manner as to tend to hold the plunger 14 in projected position, and it will thus be seen that when pressure is applied to the thumb piece 26 the gear 22 will be driven and the spring 25 extended but as soon as pressure is relieved the spring 25 will return the plunger to original position and owing to the clutch arrangement the pawl 46, slips over the ratchet teeth 45 within the gear 22 and the 80 pinion 21 may freely rotate in the reverse direction without driving the gear.

The fan consists of a hub 27 which is arranged to be secured to the outer end of shaft 24 as shown in Figures 1 and 2, and 100 this hub is provided with a pair of plates 28 between which the hub members of the fan blades are arranged. A tongue 29 is formed on one of the plates 28 and is adapted to be bent into the position illustrated 105 in Figure 1 so as to pass through the notch 30 of the hub member 31 on the stationary fan blade 32 and it will thus be seen that

upon rotation of the shaft 24 the blade 32 will be driven without lost motion.

The hub member 33 of the foldable fan blade 34 is provided with an arcuate recess 35 which forms stops 36 and 37 which are adapted to be engaged by the tongue 29 when the device is set in operation. A similar arcuate cutaway portion 38 forming stops 39 and 40 are arranged on the hub member of the fan blade 41. It will thus be seen that the fan blades may be folded into the position illustrated in Figure 1 when the device is at rest but as soon as the device is set in motion it will be obvious that the tongue 29 will move in the recesses 35 and 38 respectively, until it engages the slots 37 and 40 respectively, at which time the fan blades will have assumed the position illustrated in Figure 2.

20 While in the foregoing there has been shown and described the preferred embodiment of this invention, it is to be understood that certain minor changes, in the details of construction, combination and arrangement of parts may be resorted to without departing from the spirit and scope of the invention as claimed.

What is claimed is:—

1. In a rotary hand fan, a centrally slotted reciprocating plunger, rack teeth formed on one edge of said plunger, a base plate, an arm extending horizontally from said base plate substantially midway between the ends thereof, an L-shaped cover plate, a leg on said cover plate substantially parallel to and disposed oppositely to said arm of said base plate, a second leg on said cover plate in a plane in spaced relation and parallel to the plane of said first mentioned leg and adapted to maintain the face of said plunger in position, a shaft jour-

nalled in said arm and said second leg near the ends thereof, a pinion loosely mounted on said shaft and in engagement with the rack teeth of said plunger, a gear on said shaft operatively connectible to said pinion on the downward movement of said plunger, a driven shaft journaled in said L-shaped plate near the bend thereof and in said base plate, a guide arranged in the slot of said plunger and between said second leg of said cover plate and said base plate, and a pair of screws passing through said cover plate, guide, and base plate, for holding said shafts, gears, plates and plunger together as a unit.

2. In a rotary hand fan a plunger having a longitudinal central slot therein, rack teeth formed on one of the outer edges of said plunger, a T-shaped base plate, an L-shaped cover plate, a horizontal leg on said cover plate, a horizontal arm on said base plate, said leg being substantially parallel to and disposed oppositely to said arm of said base plate, a guide arranged in the slot of said plunger of substantially the same thickness as said plunger, a driven shaft supported by said plates, means operatively connected to said shaft for driving said shaft on the downward movement of said plunger, and means for holding said plates together with said plunger, said guide, and said driving means between said plates and with the upstanding leg of said cover plate spaced from said base plate a distance equal substantially to the thickness of said plunger.

Signed at New York, in the county and State of New York, this 11th day of June, 1921.

DOMENICO MARAZZO.
